AIR VALVE

William J. Daubenspeck, Cleveland, Ohio, assignor to The Ignition Manufacturing Company, Cleveland, Ohio, a Corporation of Ohio

Application September 22, 1927, Serial No. 221,239. Renewed June 7, 1932.

4 Claims. (Cl. 251—127)

This application is a continuation in part of my pending application Serial No. 78,362, filed December 30, 1925 now Patent Number 1,789,561 upon improvements in spark plugs.

- 5 My invention relates to air valves and particularly to automatically-operating sliding valves. More particularly, the invention relates to a valve of this character adapted for use with the spark-plugs of internal combustion engines, 60 10 the purposes of the invention being thereby to provide means whereby a leaner combustible mixture acts even more effectively than a richer mixture in the same engine not provided with my improved air valve, thereby effecting a very 65 15 material saving in fuel cost and a material reduction in the combustible fuels in the exhaust; whereby supplementary air is supplied to the mixture in the cylinder to more completely burn the combustible vapors in the cylinder; whereby 70 20 a surplus of oxygen is provided, especially at the spark-plug to insure complete combustion of all carbon at this point; whereby the spark-plug is maintained clean and cool; whereby accumulated carbon is removed from the engine piston tops 75 25 and the valve tops and the manifold; whereby short-circuiting across the porcelain of the spark-plugs is eliminated; whereby back-firing is avoided; whereby the quick pick-up and power 80 30 and general operation of the engine is greatly 85 35 improved; and whereby the work and time necessary to start a cold engine is greatly reduced.

The annexed drawing and the following description set forth in detail certain means embodying my invention, such disclosed means, however, constituting but one of the forms in which the principle of my invention may be applied.

40 In said annexed drawing, Figure 1 is a vertical cross-section through a conventional spark-plug structure in which my improved air valve has been incorporated, the valve being shown in its closed position;

45 Figure 2 is a side elevation of said spark-plug and air valve;

50 Figure 3 is an enlarged vertical section of the valve in the position shown in Figure 1, fragmentary portions of the spark-plug body being also shown;

55 Figure 4 is a view similar to Figure 3, the valve being shown in its open position; and

60 Figure 5 is an enlarged plan section, taken in the plane indicated by the line V—V, Figure 1, the valve being shown, however, in its open position.

65 My improved air valve comprises a particular

assembly of constituent parts, hereinafter fully described, and is capable of general application, but I have illustrated the preferred application of the same, and shall hereinafter so describe it, as incorporated with the spark-plug structure forming part of an internal combustion engine, the air admitted by the valve in such structure to be mixed with the fuel admitted by the usual carburetor construction, with results hereinbefore mentioned as the objects of the invention.

70 Referring to the annexed drawing, in which the same parts are designated by the same respective ordinals in the several views, spark-plug members 1 and 2 are assembled and interconnected to form a conventional chambered spark-plug casing provided with the standard porcelain unit 3 longitudinally intersected by the conductor rod 4 having the upper binding post portion 5 and the lower electrode 6. The 75 plug casing member 1 and the lower part of the porcelain unit 3 are spaced to provide a chamber 7, plainly shown in Figure 1. I mount my improved air valve in the wall of the casing member 1 and in a suitable manner necessary to effect the valve operation and the results hereinafter described. The manner in which I have incorporated the valve, as shown in the accompanying drawing, is as follows.

80 The outer face of the casing member 1 is formed with a 85 hole 8 whose peripheral wall is threaded to receive a tubular valve support 9 having a transverse groove 10 in its outer face by means of which it may be secured in the casing member 1 through the medium of a suitable tool co-operating with the groove 10, this particular construction also providing for properly seating the valve, as hereinafter fully described. The outer 85 face of the casing member 1 is formed with a 90

hole 8 whose peripheral wall is threaded to receive a tubular valve support 9 having a transverse groove 10 in its outer face by means of which it may be secured in the casing member 1 through the medium of a suitable tool co-operating with the groove 10, this particular construction also providing for properly seating the valve, as hereinafter fully described. The outer 95 face of the casing member 1 is formed with a 100

hole 8 whose peripheral wall is threaded to receive a tubular valve support 9 having a transverse groove 10 in its outer face by means of which it may be secured in the casing member 1 through the medium of a suitable tool co-operating with the groove 10, this particular construction also providing for properly seating the valve, as hereinafter fully described. The outer 105 face of the casing member 1 is formed with a 110

shown in Figure 4. A port 23 is provided which affords communication between the valve support chamber 22 and the plug-casing chamber 7, this port 23 being formed in a partition wall 26 formed in the casing member 1. When the valve is in its open position, the bottom 24 thereof is seated upon the outer face 15 of partition wall 26, but when the valve is in its closed position, said valve face 24 is spaced from the wall face 15, as indicated by the ordinal 11, Figure 3. This face 15 of wall 26 constitutes a stop limiting the opening movement of the valve. Although the valve is seated upon the face 15 of the partition wall 26, when in its open position, I provide for open entry of the air to the chamber 7 by forming the inner end of the valve with a transverse channel 25 communicating at its ends with the space 21 surrounding the valve portion 16 and communicating intermediate its ends with the port 23, as plainly shown in Figures 3 and 5.

The elements hereinbefore described are relatively proportioned and spaced to insure a valve operation accomplishing the desired results. For purposes of illustration, I will state that one effective arrangement and proportioning consists in providing a valve throw of $1/64''$, i. e., the space 11 is $1/64''$ wide; in forming the port 23 of $1/16''$ diameter, in providing a clearance of $.015''$ for the space 19 between the valve portion 18 and the support 9; in providing a clearance of $.007''$ for the space 21; and in providing a comparatively large vent area 20, possibly $1/64''$ for the space between the valve portion 17 and the valve support 9.

The operation of my improved air valve in the spark-plug structure is as follows. The downward stroke of the engine piston creates a vacuum and suction which opens this improved air valve and permits air to enter the casing chamber 7 in the manner plainly shown in Figures 4 and 5. This air strikes the porcelain unit 3 and is broken up by said unit, the air being distributed all around the unit, and at the same time the action of the air maintains the unit clean and cool. This air is drawn into the cylinder where it is thoroughly mixed with the fuel drawn from the carburetor through the cylinder inlet valve, resulting in a comparatively lean but very effective mixture of gas and air. This combination results in a very satisfactory combustion, giving the engine increased power with a minimum gas consumption. The upward stroke of the piston closes the air valve, resulting in a maximum compression and the reduction of the mixture to a perfect state for combustion.

The results hereinbefore mentioned are obtained by the construction and operation described, the comparatively large seating area of the valve, together with the other described features, resulting in perfect operation of the air valve over a long period of time without inducing any leakage or other difficulties encountered in constructions heretofore designed for feeding air through spark-plugs, insofar as I am acquainted with such previous constructions. The difficulty of induced leakage is particularly evident in valves of this character of the ball-valve type, the suction apparently preventing efficient seating of the valve when it should be closed, due to various causes such as the bouncing action of the valve, the lack of proper guiding, and the limited seat area which is continuously changing.

It is evident that a suitable tool cooperating with the groove 10 will provide through the support 9 for a proper adjustment of the air valve to its seat 15 upon the partition wall 26. Also, the portion 17 of the air valve can be ground into its seat 13 in the valve support 9 by rotating the valve by means of a suitable tool adapted to engage the transverse channel 25 formed in the end of the valve portion 16. The outer portion 18 of the air valve projects somewhat beyond the face of the valve support 9 so as to permit the inspection of the valve operation from the outside of the spark-plug. This construction also permits the valve to be held open by pressing against the outwardly projecting end, whereby the valve seat and channels can be cleaned by blowing hot gases therethrough and whereby the valve can be tested. Also, by means of this projecting valve end, the valve can be agitated to start its operation if it shows a tendency to stick.

Although as perfect a mixture of gas and air cannot be obtained from the carburetor alone, as with the combination thereof with my improved air valve, still much of the fuel adjustment for different running requirements can be obtained by adjusting the carburetor instead of adjusting my improved air valve which cooperates therewith.

What I claim is:

1. An improved assembly for air valves comprising a chambered body formed with a hole in its outer face, a tubular valve support mounted in said hole, a perforated partition wall between the chamber of said body and the interior of said valve support, the exterior surface of said partition wall forming a valve stop, a freely reciprocatable valve disposed in said support and formed with longitudinal peripheral portions spaced from the walls of said support and a peripheral portion adapted in one position of said valve to be spaced from the walls of said support and in another position of said valve to be seated upon one of said walls, one of said longitudinal peripheral portions extending outside of said support and means affording communication between the perforation of said partition wall and the space surrounding said longitudinal peripheral portions of said valve.

2. An improved assembly for air valves comprising a chambered body formed with a hole in its outer face, a tubular valve support mounted in said hole, a perforated partition wall between the chamber of said body and the interior of said valve support, the exterior surface of said partition wall forming a valve stop, a reciprocating valve disposed in said support and formed with longitudinal peripheral portions spaced from the walls of said support and a peripheral portion adapted in one position of said valve to be spaced from the walls of said support and in another position of said valve to be seated upon one of said support walls, and means affording communication between the perforation of said partition wall and the space surrounding said longitudinal peripheral portions of said valve, said support being adjustable toward and from said partition wall.

3. An improved assembly for air valves comprising a chambered body formed with a hole in its outer face, a tubular valve support mounted in said hole, said body having a perforated partition wall affording communication between its chamber and the interior of said valve support, the exterior surface of said partition wall forming a valve stop, a freely reciprocatable

valve disposed in said support and formed with
end longitudinal peripheral portions spaced from
the walls of said support and an intermediate
connecting diagonal surface portion adapted in
5 one position of said valve to be spaced from
the walls of said support and in another position
of said valve to be seated upon one of said
walls, the inner end of said valve being formed
10 with a transverse channel affording communica-
tion between the perforation of said parti-
tion wall and the space surrounding the inner
longitudinal peripheral portion of said valve, the
outer end of the valve projecting somewhat ex-
teriorly of the outer face of the valve support.

15

4. A valve comprising a cage adapted to be
fitted adjustably in an apertured body and a
valve member freely reciprocatable within said
cage, said cage and valve member having corre-
sponding loosely fitting end guide portions and
80 corresponding intermediate seat portions closely
contacting in the closed position of the valve,
the outer guide portions differing in cross sec-
tional area from the inner guide portions, and
the clearance between the corresponding guide
85 portions being smaller for the guide portions
having the larger cross sectional area.
